DESIGN FOR AN AIRPLANE

Carl W. Scott, Grosse Point Farms, Mich., assignor to Curtiss-Wright Corporation, a corporation of Delaware

Application April 19, 1943, Serial No. 109,995

Term of patent 14 years

(Cl. D71—1)

To all whom it may concern:

Be it known that I, Carl W. Scott, a citizen of the United States, residing at Grosse Point Farms, in the county of Wayne, State of Michigan, have invented a new, original, and ornamental Design for Airplanes, of which the following is a specification, reference being had to the accompanying drawings, forming a part thereof.

In the drawings:

Fig. 1 is a top plan view of an airplane showing my new design.

Fig. 2 is a front elevational view of the airplane with landing gear retracted.

Fig. 3 is a side elevational view with the landing gear extended.

Fig. 4 is a top perspective view of the airplane as it appears when in flight.

I claim:

The ornamental design for an airplane, substantially as shown.

CARL W. SCOTT.
